UNITED STATES PATENT OFFICE.

JEAN BAPTISTE MARTIN, OF ST. POLYCARPE, CANADA, ASSIGNOR OF ONE-HALF TO DIEUDONNE MARTIN, OF ST. POLYCARPE, CANADA.

COMBINATION-DERRICK.

SPECIFICATION forming part of Letters Patent No. 727,658, dated May 12, 1903.

Application filed May 2, 1902. Serial No. 105,577. (No model.)

To all whom it may concern:

Be it known that I, JEAN BAPTISTE MARTIN, a subject of the King of Great Britain, residing at St. Polycarpe, county of Soulange, Province of Quebec, Canada, have invented certain new and useful Improvements in Combination-Derricks; and I do hereby declare that the following is a full, clear, and exact description of the invention, such as will enable others skilled in the art to which it appertains to make and use the same.

My invention relates to an improved hoisting apparatus of the derrick type, combined with a windlass attachment of special adaptability.

The object of my invention is to produce an interchangeable apparatus which may be used for a variety of purposes and which when not in use may be folded up and knocked down in condition for easy handling and shipment.

One feature of this invention consists in the construction of the derrick-beams, which are in the form of a pair of shear-shaped members pivoted at their upper ends and adapted to be removably secured at their lower ends to the base-frame, which carries the windlass.

Another feature of my improvement resides in the mounting of the base-frame and the provision of means for securing the upright derrick-frame thereto, this frame being further provided with suitable rollers, which enable the apparatus to be readily shifted, and the longitudinal beams thereof being provided with rearwardly-projecting handles, so that the same may be managed and rolled from place to place in the same manner as an ordinary wheelbarrow or hand-truck.

Other objects and novel features of my invention will appear from the following description and are particularly brought out in the claims.

The invention consists in the combination and arrangement of parts hereinafter set forth and claimed.

I have shown the most approved form of my improved derrick apparatus in the accompanying drawings, wherein—

Figure 1 is a perspective view of the apparatus complete. Fig. 2 is a plan view of the base-frame, showing certain portions thereof

in section. Fig. 3 is a vertical central section of the apparatus in position for hoisting. Fig. 4 is a separate perspective view of the upright frame, and Fig. 5 is a partly-sectional elevation showing the application of the windlass to a horizontal drawing operation.

The same numerals of reference denote like parts in all the figures of the drawings.

My improved apparatus consists in the main of two separable frames—that is to say, an upright frame 6 and a base-frame 7—the former of which consists, as shown in Fig. 4, of a double pair of shear-legs, each consisting of strut-posts 8 and tie-posts 9, pivoted together at their upper ends by a transverse bolt 10, which passes from side to side and through the center of a roller 11, which acts to retain the two members of each pair of shear-legs at the proper distance apart. The two members 8 of each pair are appropriately connected together by cross-beams 12, and the two tie members 9 are likewise connected by cross members 13, and each of the members 8 and 9 is appropriately recessed or mortised, as shown at 14 and 15, to enable the two members 8 and 9 of each pair to be folded together and laid flat on a car or vehicle when it is desired to transport the derrick or to prepare it for shipment. The two strut-posts 8 are each provided at their lower ends with a downwardly-projecting pin 16, which is adapted to be seated in a suitable socket 17, formed at the front end of one of the longitudinal side beams 18 of the base-frame 7, and the lower ends of the tie members 9 are likewise provided with a pair of hooks 19, which are passed transversely through the beams 9, as shown at 20, and securely bolted thereto by nuts 21, passing over their threaded ends. These hooks 19 depend to a level with the lower ends of the members 9, which are beveled at their lower ends, as shown at 22, in order to enable them to sit flat upon the frame-beams 18 of the windlass, and the hooks 19 are adapted to engage in the eyes of suitable eyebolts 23, passed through vertical apertures in the beams 18 and secured thereto by nuts 24 upon their lower sides. In order to hold the two shear-legs 8 and 9 on each side of the upright frame at proper relative distances when mounting the frame in place

upon the base-frame, I furthermore preferably provide a pair of plates 25, which are pivoted at one end upon pins 26, secured in the members 9, and at their other ends are 5 formed with vertical slots 27, adapted to embrace pins 28, driven into the strut-posts 8.

The base-frame 7 consists of two longitudinal beams 18, as hereinbefore referred to, secured together in parallel relation at the 10 same distance as the two sides of the upright frame by means of cross-beams 29 connecting them, and, furthermore, at their front ends they are connected by the axle 30 of a pair of truck rollers or wheels 31, having flattened 15 rims or fellies 32, whereby to offer a wide area to sustain the upright frame and prevent the wheels 31 from crushing into the ground when the apparatus is rolled along. On the rear ends of the beams 18 are formed a pair of handle-bars 33, by which the rear end of the apparatus is adapted to be raised and turned about the axis 30 in the manner of an ordinary hand-truck or barrow when it is desired to roll the derrick from place to place. On the 20 upper side of this base-frame, just in the rear of the upright frame, is mounted a windlass, which comprises a winding-drum 34, mounted upon an arbor 35, journaled in a pair of pillow-blocks 36, secured upon the respective 25 beams 18 by holding-down bolts 37. To the ends of the drum are securely attached ratchet-wheels 38, which are engaged by drag-pawls 39, pivoted at 40 upon hand levers or bars 41, which levers or bars are themselves 30 mounted to turn loosely upon the arbor 35. The weight of the pawls 39 holds them in contact with the teeth of the ratchet-wheels 38 and causes them to slip thereover when the lever-bars 41 are raised, and in order to enable 35 a weight raised by the derrick to be lowered I provide levers 42, which are pivoted, as at 43, to straps 44, mounted upon the levers 41, and connected, as at 45, to the pawls 39, so that by pressing down upon the rear 40 end of the lever 42, which is arranged to be operated by the hand resting upon the lever 41, the pawl 39 can be raised.

In order to provide further against the back turning of the ratchet-wheels 38 and to support a weight in any given position, I also 45 preferably provide upon the lower side of the ratchet-wheels a pair of stationary pawls 46, which are pivoted to the beams 18, as shown at 47, and spring-pressed against the teeth of the ratchet-wheels by means of suitable leaf-springs 48. When the apparatus is in use as a derrick, a cord or other connection 49 is wound around the drum 34 and secured at one end thereto and thence passed upwardly and 50 around the roller 11, from which it is let down, and may have a suitable grapple, such as a pair of sister hooks 50, attached to the lower end thereof to seize and raise any desired weight 51.

65 In case it is desired to produce a horizontal draft upon the connection 49 the upright frame may be removed by tipping it back-

wardly until the hooks 19 are disengaged from the eyebolts 23, when the derrick may be removed, and in order to secure or anchor the 70 windlass-frame against horizontal displacement, due to the reaction of the rope 49, I provide a pair of downwardly-projecting spikes 52, which are braced by bracket-irons 53 and project from the lower side of the beams 18. 75 In Fig. 5 I have shown this application of my apparatus in the operation of drawing a freight-car 54 along the track 55, which is done by engaging the hook 56, carried by the end of the rope 49, with the draw-link 57 of the 80 car and anchoring the spikes 52 behind one of the ties 58, the base-frame being caused in this case to rest in the center of the track, between the two rails thereof.

The operation of winding the cord 49 about 85 the drum 34 may be done by two men, each working at one of the hand-levers 41, and in cases where the force upon the rope is not too great these hand-levers will ordinarily be worked alternately, so as to produce a continuous rotation of the drum 34; but where the reaction of the rope is very great the two operators will depress their respective levers simultaneously, so as to produce double the power that could be produced by one lever. 95

From the above description the numerous advantages of my combination-derrick will be obvious, as well as its ready adaptability to all conditions and the ease with which it may be knocked down for shipment, as well 100 as transported in mounted position from place to place.

While I have shown in the accompanying drawings the preferred form of my invention, it will be understood that I do not limit 105 myself to the precise form shown, for many of the details may be changed in form or position without affecting the operativeness or utility of my invention, and I therefore reserve the right to make such modifications as 110 are included in the scope of the following claims.

Having thus described my invention, what I claim, and desire to secure by Letters Patent, is—

1. A derrick comprising a horizontal frame having longitudinal side beams, a vertical foldable frame mounted thereon and resting on said side beams, a pair of rollers mounted upon an arbor at the front of said horizontal frame, and a pair of handles formed at the rear end of said horizontal frame upon the end of said side beams.

2. A derrick comprising a horizontal frame, a vertical foldable frame removably mounted thereon, a pair of rollers mounted upon an arbor at the front of said horizontal frame, and a pair of handles formed at the rear end of said horizontal frame, in combination with a windlass mounted on said horizontal frame.

3. A derrick comprising a horizontal base-frame having a pair of longitudinal side beams, rollers mounted to turn on an arbor at the front end of said frame, a vertical frame

consisting of a pair of strut-posts and a pair of tie-posts connected at their upper ends and adapted to be removably secured at their lower ends to the front end of said first-named frame, and handle-bars secured upon the rear ends of said longitudinal beams.

4. A derrick and windlass comprising a horizontal frame having a pair of longitudinal side beams and cross-beams connecting them, an arbor carrying rollers mounted upon the front ends of said longitudinal beams, handles formed on the rear ends thereof, a windlass mounted thereon, and a foldable frame removably secured thereto.

15 5. A derrick comprising a horizontal frame having a pair of longitudinal side beams connected by cross-beams, a drum mounted transversely upon pillow-blocks secured to said side beams, and an upright frame consisting of two foldable members pivoted at their upper ends and removably secured at their lower ends upon said side beams.

25 6. A derrick comprising a horizontal frame having a pair of longitudinal side beams, cross-beams connecting them in parallel relation, an arbor carrying rollers mounted to turn in the front ends of said side beams, handles projecting from the rear ends thereof, anchor-posts projecting from the lower 30 side thereof, pillow-blocks mounted thereon, a winding-drum having winding means co-acting therewith and adapted to turn in said

pillow-blocks, and an upright frame removably mounted on the front end of said horizontal frame.

7. A derrick comprising a horizontal frame having a pair of longitudinal side beams and a pair of cross-beams connecting them in parallel relation, a pair of rollers mounted on an arbor rotatably mounted in the front ends 40 of said longitudinal beams, anchor-posts depending from said frame, handle-bars formed at the rear end thereof, a pair of pillow-blocks mounted on the respective side beams, a winding-drum mounted on an arbor to turn in said 45 pillow-blocks, a derrick-frame comprising a pair of parallel connected strut members and a pair of parallel connected tie members pivoted thereto at their upper ends, anchor-pins projecting from the lower side of said strut- 50 posts into suitable sockets in the front ends of said longitudinal beams, hooks secured at the lower ends of said tie members and adapted to engage removably with eyes secured to said longitudinal beams, and a roller mounted at the upper end of said upright frame upon the pivot thereof, substantially as described.

In witness whereof I have hereunto set my hand in the presence of two witnesses.

JEAN BAPTISTE MARTIN.
